(57) **CLAIM**

The ornamental design for a hammer as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 illustrates a left perspective view of the hammer showing the new design.

FIG. 2 illustrates another left perspective view the hammer in FIG. 1.

FIG. 3 illustrates a right perspective view of the hammer in FIG. 1.

FIG. 4 illustrates a perspective top view of the hammer in FIG. 1.

FIG. 5 illustrates another perspective top view of the hammer in FIG. 1.

FIG. 6 illustrates a left perspective bottom view of the hammer in FIG. 1; and,

FIG. 7 illustrates a right perspective bottom view of the hammer in FIG. 1.

1 Claim, 7 Drawing Sheets
(7 of 7 Drawing Sheet(s) Filed in Color)
